UNITED STATES PATENT OFFICE.

ELMER FUZESSERY, OF AKRON, OHIO.

RESILIENT HEEL.

1,416,279.

Specification of Letters Patent. Patented May 16, 1922.

Application filed April 22, 1920. Serial No. 375,690.

To all whom it may concern:

Be it known that I, ELMER FUZESSERY, a citizen of the United States, residing at Akron, in the county of Summit and State of Ohio, have invented new and useful Improvements in Resilient Heels, of which the following is a specification.

This invention relates to resilient heels and has particular relation to a heel lift composed of rubber, rubber composition or similar substance.

The main object of the invention is to provide a lift which when attached to a shoe heel will adhere closely thereto and which will not in use develop an unsightly gap between the heel proper and the lift.

The above and other objects are accomplished by the novel construction, combination and arrangement of parts hereinafter described and illustrated in the accompanying drawing, wherein I have shown a preferred embodiment of the invention, it being understood that the invention is capable of various adaptations and that changes and variations may be made and substitutions resorted to which come within the spirit of the invention or the scope of the claims hereunto appended.

In the drawings in which similar numerals of reference are employed to indicate corresponding parts throughout the several views,

Figure 1 is a plan view of the attaching face of a heel lift constructed in accordance with this invention,

Figure 2 is a longitudinal sectional view of same taken approximately on line 2—2 of Figure 1,

Figure 3 is a cross sectional view of same taken on line 3—3 of Figure 1,

Figure 4 is a cross sectional view of a portion of a shoe illustrating the manner in which the lift is attached thereto.

Figure 5 is a plan view of the wearing face of said lift.

Referring now to the drawings in detail, the numeral 6 is used generally to denote the wearing face of the lift and the numeral 7 the attaching face. The numeral 8 is used to denote the breast and the numeral 9 the rear and lateral sides of the heel. The wearing face of the heel is provided with a configuration in bas-relief in the form of a rib 10 which is positioned thereon in spaced relation to the sides 9 of the lift. Each end of the rib 10 terminates relatively remote

from the breast 8. The outer side 11, the inner side 12 and the ends 13 of the rib 10 are normally disposed at a right angle to the wearing face 6 of the lift. The attaching face 7 is provided with a depressed configuration in the form of a shallow groove 15 which has a bottom 14 which is parallel with the face of the rib 10 and is substantially coextensive therewith. The groove 15 has an outer wall which is inclined upwardly from the bottom 14 to the upper edge of the sides 9 and an inner wall which is inclined inwardly at approximately the same angle. The end walls of said groove are inclined upwardly to the upper edge of the breast 8. The central portion of the attaching face 7 is flat and slightly lower than the upper edge of the sides 9 and extends outwardly in the same plane to the upper edge of the breast 8. The numeral 16 is used to denote nail holes which are positioned in spaced relation in the rib 10 and extend through the top of the lift to the embedded washers 17.

In attaching the lift to a shoe heel, the attaching face is first placed in contact with the face of the heel proper 19 and nails 18 or other suitable fastening means are driven into the holes 16 until the head of the nail is in contact with the washers 17. The nails are driven into the face of the heel proper until the face of the rib 10 is drawn into the same plane with the wearing face 6 of the lift and the bottom of the groove 14 is in contact with the face of the heel proper 19.

It will thus be seen that when the lift is attached to a heel, the entire area of the attaching face is held flat against the face of the lift 19 and that the wearing surface of the heel is parallel thereto. It will also be seen that when the lift is thus attached, it will be distorted and a groove 20 will be formed entirely around the rib 10 and it will also be noted that the upper edge of the sides 9 will be held in forced contact with the face of the heel 19.

While I have shown and described the invention as applied to a heel lift, it is apparent that the same may be applied to a rubber heel.

Having thus described my invention what I claim as new and desire to secure by Letters-Patent is:—

1. An elastic heel lift provided on its wearing face with a rib of rectangular cross

section which projects therefrom in parallel spaced relation to the edge thereof and provided on its attaching face with a groove having diverging side walls and a bottom wall which is of substantially the same area as the wearing face of said rib, the outer wall of said groove terminating coincident with the edge of the lift.

2. An elastic heel lift provided on its wearing face with a rib of rectangular cross-section which projects therefrom in parallel, spaced relation to the edge thereof, each end of said rib terminating in spaced relation to the breast of the lift and provided on its attaching face with a bottom wall which is of substantially the same width as the wearing face of said rib and having diverging side walls, the outer wall of said groove terminating at the edge of said lift,

20 said groove provided at each end with an inclined wall which extends upwardly to the breast of the lift.

3. A heel lift comprising an elastic body provided on its wearing face with a low rib of rectangular cross section which projects therefrom in parallel spaced relation to the edge thereof, each end of said rib terminating in spaced relation to the breast of the lift; said lift further provided on its attaching face with a groove having a bottom wall of substantially the same area as the wearing face of said rib and having diverging side walls and outwardly inclined end walls, the upper edge of the outer wall extending

along the curved edge of the lift and the upper edge of the end walls extending along the breast edge thereof.

4. A heel lift comprising a body of resilient material, provided on its wearing face with a low flat rib of rectangular cross section which is positioned thereon in spaced parallel relation to the peripheral edge of the lift, nail receiving openings in said rib, a groove formed in the attaching face thereof so that the face of the rib will lie in the same plane with the wearing face of the lift when the same is distorted by being attached to a heel.

5. A heel lift comprising a body of resilient material, provided on its wearing face with a low rib of rectangular cross section which is positioned thereon in parallel spaced relation to the peripheral edge of the lift, nail receiving openings in said rib, the attaching face of the lift being provided with a channel which is positioned therein directly opposite said rib, the outer wall of said channel being inclined upwardly from the bottom thereof to the peripheral edge of the lift and the inner wall of said channel being inclined upwardly at a similar angle, the central portion of said attaching face being flat and disposed in a plane lower than the peripheral edge of said attaching face, substantially as herein set forth.

In testimony whereof I have hereunto set my hand.

ELMER FUZESSERY.
